[57] CLAIM

The ornamental design for a cast cover, as shown and described.

DESCRIPTION

FIG. 1 is a right elevational view of a cast cover showing our new design;

FIG. 2 is a left side elevational view thereof;

FIG. 3 is a right side elevational view thereof;

FIG. 4 is a top end elevational view thereof;

FIG. 5 is a bottom end elevational view thereof;

FIG. 6 is a left elevational view thereof; and,
FIG. 7 is a front perspective view thereof, the broken line showing of the human form is for illustrative purposes only and forms no part of the claimed design.

1 Claim, 2 Drawing Sheets

FIG. 1.

FIG. 2.

FIG. 3.

FIG. 4.

FIG. 5.

FIG. 7.

FIG. 6.
